UNITED STATES PATENT OFFICE

THOMAS KOIDL, OF WELS, AUSTRIA

METHOD OF AND MEANS FOR CLOSING THE ENDS OF THE CHANNELS OF MOLDED
HOLLOW CHANNEL BRICKS AND BUILDING BLOCKS

Application filed September 3, 1930, Serial No. 479,436, and in Austria September 4, 1929.

This invention relates to a method of closing up the open ends of the channels of hollow molded bricks or building blocks and to a device for the carrying out of this method. A known method of accomplishing the described end is to cleave the ends of the walls and/or of the ribs between the channels while in the plastic state and to bend over the flaps thus formed into contact with each other. In hollow bricks and building blocks with one or more channels closed at one end or at both ends in accordance with this method the arched bridge over each channel and exhibits a narrow crack, so that the channels are not completely closed. Finally this known method is only suitable for application in connection with particularly plastic molding material of unusually slight power of adhesion to tools, e. g. modelling clay and the like.

The present invention provides a method of closing up the open ends of the channels of freshly molded hollow bricks and building blocks which consists essentially in the formation and uniting of the above-mentioned known flaps of the partitions or ribs between the channels and/or of the walls by means of a combined rubbing and rolling of the material of these flaps during the cleaving and closing process. The cleaving and rolling treatment is accomplished by means of rapidly rotating profile rollers which are mounted on a common driven shaft with parallel guiding, and are first pressed into the material of the ends of the walls and/or of the ribs or partitions between the channels and then moved at a controllable rate of progress along these walls and/or ribs or partitions.

The cleavage of the walls and/or ribs or partitions in accordance with this method enables a completely closed arched bridge to be formed over each channel end, since the combination with the rolling of a rubbing or finishing action due to the rapid rotation of the rollers causes the material of the flaps to become united to form a homogeneous whole. It is moreover possible, by the application of this method, to make use of inferior raw materials which are liable to

crack for the manufacture of one-sidedly or totally closed hollow bricks and building blocks, without danger of a faulty uniting of the cleft portions.

A suitable form of device for the carrying out of the above-described method as applied to a multi-channel brick is illustrated by way of example in the accompanying drawings, in which:—

Fig. 1 is a side elevation of the device for the carrying out of the method according to the invention, as seen from the inner side.

Fig. 2 is a section taken on the line I—I of Fig. 1.

Fig. 3 illustrates a detail of the construction of the same device, in section.

Fig. 4 illustrates diagrammatically the manipulation of the device in connection with a freshly detached molded brick which has just left the die-press.

Fig. 5 is a perspective view in section of a one-sidedly closed hollow channel brick.

The device consists of a plate *b* which may be provided with a handle *a* and from which project arms or brackets *c* to which guides *d* are attached. Sleeves *e* connected together by means of a tie-piece *f* are adapted to be easily slidable along these guides. To the sleeves *e* are attached the bearings *g* for a shaft *h* which is adapted to be set in rapid rotation by means, for example, of a flexible drive from a suitable driving motor.

The shaft *h* is provided at intervals corresponding to the distance between the ribs or partitions *i* of the hollow brick *j* with profile rollers *k* in front of which is mounted a templet *m* with slits *l* through which the rollers are adapted to project. The templet *m* is provided with a returned guiding edge *n* bent at right angles, and is mounted on bolts *o* which are guided in tubular projections *p* on the plate *b* under the action of springs *q*. In this manner the templet *m* and the plate *b* are rendered capable of being approached towards each other up to within a certain limit, for the purpose of pressing the rollers *k* through the slits *l* in the templet *m* which is applied to the face of the hollow brick into the ribs or partitions of the latter (Fig. 4). The rapidly rotating rollers are adapted to

carry out a forward movement the rate of which depends upon the frictional resistance between the rollers and the material of the ribs or partitions. During this movement the sleeves *e* together with the shaft *h* are slid along the guides *d*, and the material brought in contact with the surface of the rollers is submitted apart from the rolling action to a kind of rubbing or smoothing action which effects the homogeneous uniting of the cleft portions of the ribs or partitions and at the same time prevents the adhesion of the plastic material to the surface of the rollers. The speed of the forward movement of the rollers can be regulated either by means of adjustable springing means inserted between the fixed and the movable parts of the device or, most simply, by means of a thumb latch *r* as indicated in Fig. 4, in such a manner that the forward movement is not too rapid, while the rolling action is accomplished at a rate adapted to the nature of the material used.

Under certain circumstances the nature of the material used can make it desirable to provide a preliminary cutter in the form of a cutting wire in front of the shaping rollers, so that the material of the ribs or partitions is opened in readiness for the impress of the rollers.

As is indicated in Fig. 4 it is also possible for both end surfaces of the shaped brick to be treated in the described manner, and also for the whole process of the closing of the open ends of the channels to be carried out simultaneously with the removal of the brick from the orifice of the press.

I claim:—

1. A method of closing up the open ends of the channels of hollow channel bricks and building blocks which consists in cleaving the end surfaces of the outside walls and of the ribs between the said channels, forcing the flaps thus formed apart, and uniting the said flaps across the said open ends by means of rollers adapted to exercise a combined rolling and rubbing action upon the material of the said walls and ribs.

2. Apparatus for closing the open ends of the channels of hollow bricks and building blocks comprising adjustable profile rollers arranged to be rotated at a high speed, means for pressing the said rollers into the end surfaces of the ribs of a brick or block, and means for imparting a regulatable forward movement to the said rollers.

3. Apparatus for closing the open ends of the channels of hollow bricks and building blocks, comprising a templet for application to the end of a brick or block and having slots, a side plate connected to the templet for movement toward and from the same, guide elements carried by the side plate and arranged on the side thereof opposed to the templet, sleeves slidably mounted on said

guide elements and a revoluble shaft mounted in bearings with which the sleeves are provided, said shaft having profile rollers thereon arranged to be moved by corresponding movement of the side plate through the slots of the templet into engagement with the ribs of the brick or block.

4. Apparatus as claimed in claim 3, in which the side plate is provided with cylinders extending toward the templet, the latter is provided with plunger elements movable longitudinally in the cylinders and also including springs in the cylinders and bearing against the inner ends of the plunger elements.

5. Apparatus as claimed in claim 3, including means whereby the forward movement of the rollers incident to their frictional contact with the work may be regulated.

6. Apparatus as claimed in claim 3, including means whereby the forward movement of the rollers incident to their frictional contact with the work may be regulated and comprising a thumb latch and in which the side plate is provided with a handle contiguous to the thumb latch.

7. Apparatus as claimed in claim 3, including means for limiting the extent of movement of the side plate toward the templet and thereby correspondingly limiting the extent to which the profile rollers may project through the slots of the templet.

8. Apparatus as claimed in claim 3, in which the templet is provided at one side with a return end to bear against one side of the brick or block.

In testimony whereof I affix my signature.

THOMAS KOIDL.
